UNITED STATES PATENT OFFICE

125,795

DESIGN FOR A BARBER'S CABINET

Daniel Du Bois, Poughkeepsie, N. Y.

Application March 11, 1940, Serial No. 90,834

Term of patent 14 years

To all whom it may concern:

Be it known that I, Daniel Du Bois, a citizen of the United States of America, residing at Poughkeepsie, in the county of Dutchess and State of New York, have invented a new, original, and ornamental Design for a Barber's Cabinet, of which the following is a specification, reference being had to the accompanying drawing, forming part thereof.

The dominant features of the design reside in the portions shown in full lines.

I claim:

The ornamental design for a barber's cabinet, as shown and described.

DANIEL DU BOIS.
